ARTICLE FORMING APPARATUS.

John S. Stull, Chicago, Ill., assignor to Western Electric Company, Incorporated, New York, N. Y., a corporation of New York

Application November 30, 1944, Serial No. 565,915

9 Claims. (Cl. 140—103)

1

This invention relates to article forming apparatus and particularly to an apparatus for forming a terminal end of a coil.

The invention is particularly applicable to the forming of a terminal end of a vacuum tube heater coil. Such a coil may, for instance, comprise as it comes from a coiling apparatus, a coil of .005" diameter tungsten alloy wire, the coil having an outside diameter of $\frac{1}{16}$ " and a length of $\frac{1}{16}$ " each terminal end extending tangentially $\frac{1}{4}$ " from the coil at right angles to its longitudinal axis. In order to facilitate the mounting and connecting of the terminal ends of the coils into the vacuum tube structure and circuit, the tangent ends of each coil should be preferably preformed to required formations relative to the longitudinal axis of the coil. Due to the microscopic dimensions of the coils, great difficulty is encountered in handling, forming and giving the terminal ends a desired set and also providing a desired uniform formation to the ends of the coils.

An object of this invention is to provide a simple, efficient and practicable apparatus for uniformly forming and setting terminal ends of coils of the type above described.

In order to attain this object, in accordance with one embodiment of the invention as applied to the forming of one terminal end of the coil hereinbefore described, wherein the end is to extend parallel to the longitudinal axis of the coil and in alignment with the outer periphery thereof, there is provided an apparatus comprising a stationary arbor for supporting the coil, stationary and movable elements at opposite sides of the arbor so formed as to provide a pocket about the arbor for receiving the coil and a face on the stationary element for initially positioning and then guiding the terminal end during the forming thereof. The movable element is formed with a bending point about which the terminal end is bent, and an inclined forming face against which the terminal end is pressed and bent to set it. A spring actuated plunger normally urges the movable element toward the arbor to clamp a plurality of coil convolutions to the arbor. When the plunger is retracted, a spring actuates the movable element to permit the coil to be removed from or mounted on the arbor. A single hand lever pivoted on a spring pressed slideable block is provided with cam faces which successively engage the terminal end and bend it about the bending point and press it against the inclined face of the movable element to form and set it. In one position of the lever, it operatively engages

2

the plunger to cause a retraction of the movable element and, upon movement of the lever to engage an abutment, the terminal end is partially bent and continued urging of the lever against the abutment results in the lever fulcruming about the abutment to further bend the terminal end and complete the forming and setting of the terminal end.

Other objects and advantages of the invention will be apparent from the following detailed description taken in conjunction with the accompanying drawings in which:

Figs. 1 and 2 are fragmentary plan views, on an enlarged scale, of an article forming apparatus embodying the features of the invention and illustrating different operative positions thereof;

Fig. 3 is a front elevation of Fig. 2;

Fig. 4 is a greatly enlarged fragmentary vertical cross section taken on the line 4—4 of Fig. 2;

Fig. 5 is a greatly enlarged fragmentary view of a coil with a formed terminal end after removal from the apparatus;

Fig. 6 is a greatly fragmentary plan view showing the coil clamped in position and its terminal end about to be formed;

Fig. 7 is a fragmentary view similar to Fig. 6 showing the terminal end of the coil partially formed;

Fig. 8 is a vertical cross section taken on the line 8—8 of Fig. 6; and

Fig. 9 is an enlarged fragmentary perspective view of a clamping and forming element of the apparatus.

Referring now to the drawings and particularly to Figs. 1, 2 and 3, the numeral 10 indicates an irregularly shaped supporting block which is attached at one end to a vertical standard 11, which, in turn, may be mounted at its lower end on a work bench (not shown). Formed in the upper face of the block 10 are communicating, right angularly arranged slots 12 and 13, in which are mounted irregularly shaped members 14 and 15, respectively. The member 14 is fixed in the slot 12 and the member 15 is slidably fitted in the slot or guideway 13. Similarly inclined vertical adjacent faces 16 and 17, in different planes, are provided on the members 14 and 15 and such faces are arcuately grooved, as indicated at 20 and 21, respectively, to form a pocket through which freely extends an arbor 22 secured at its inner end to the fixed member 14, the outer free end of the arbor projecting a suitable distance from the forward vertical face of the block 10. The arcuate grooves 20 and 21 are formed parallel to the longitudinal axis of the arbor 22 and the

groove 21 is of smaller diameter at its inner end to provide a seat 23 for a coil 24, a terminal end 25 of which is to be formed. At the juncture of the inclined face 19 and the plane of the seat 23 on the member 15, and in line with the longitudinal axis of the coil 24, is a vertical bending edge 26, for the terminal end 25 to be referred to hereinafter. These latter details of the member 15 may be best seen by referring to Fig. 9.

In the operation of the apparatus, the slidable member 15, in one position, serves to clamp the coil 24 to the arbor 22, as shown clearly in Figs. 6 and 8. As shown, the arcuate formation 21 of the member 15 is so dimensioned and arranged that its inner face engages approximately three convolutions of the coil 24 at one side thereof and clamps them at their inner peripheries against the fixed arbor 22, the opposite sides of the coil convolutions being spaced from the arcuate face 20 of the fixed member 14. In mounting the coil 24 on the arbor 22, the tangent terminal coil end 25 to be formed is arranged to lie against an upper face 27 of the member 14, thus initially positioning the coil end. An upper face 28 on the block 10 at its left side lies in the plane of the face 27 of the member 14 and the right side of the upper face of the block lies in a higher plane than the faces 27 and 28. Fixed to the right upper face of the block 10 is a plate 29, which is notched at 32 for observation purposes, and it extends at its left end in spaced relation over the faces 27 and 28. Formed in the block 10 is a guideway 33, in which is slidably mounted a bearing block 34, to which is pivotally attached, by means of a vertically disposed pin 35, an irregularly shaped hand lever 36, which bears closely on the faces 27 and 28 at its lower face and upon the bottom face of the plate 29 at its upper face. The plate 29 is formed with an aperture 39, through which the pin 35 freely extends, the diameter of the aperture being such that at one point in the operation of the apparatus, to be described hereinafter, the block 34, pin 35 and lever 36 may be bodily shifted to the position shown in Fig. 2. A compression spring 40 carried in an aperture 41 formed in the block and communicating with the slot 12 and guideway 33 and abutting at opposite ends the stationary member 14 and the bearing block 34, serves to normally maintain the block in the position shown in Fig. 1, wherein the pin 35 is bearing against the left side of the aperture 39 of the fixed plate 29.

Mounted in an aperture 42, in the block 10, is a cup-shaped plunger 43, the aperture being interrupted by the guideway 13, in which is carried the movable member 15 and the latter member is notched at 46 to receive the plunger 43. An inclined side face 47 of the notch 46 provides a cam face, which cooperates with a similarly inclined face 48 on the plunger 43 to urge the movable member 15 to the left, as shown in Fig. 2, by the normal action of a compression spring 49 carried in the plunger 43 and bearing at opposite ends against the plunger and a stop plate 50 fixed to the block 10. In this referred-to position of the movable member 15, as hereinbefore described, the inner face of the arcuate formation 21 thereof engages the coil 24 and clamps it to the arbor 22. Fixed to the block 10 and extending into the path of the right end face of the movable member 15 is a stop pin 53. A leaf spring 54 (Fig. 3), attached at one end to the block 10 and having its opposite end entered in a notch in the movable member 15, is effective to move the member to the right to the position shown in Fig. 1 and

against the stop pin 53 when the normal action of the plunger spring 49 is overcome. In this last-referred-to position of the movable member 15, it is withdrawn from the arbor 22 and is in position to permit a coil 24 to be removed from or mounted on the arbor.

At its upper end, as viewed in Fig. 2, or its right end, as viewed in Fig. 1, the hand lever 36 carries a depending roller 55 arranged to engage and actuate the spring-pressed plunger 43 when the lever is rocked clockwise about its pivot 35 to the position shown in Fig. 1, thereby overcoming the normal action of the spring 49 and permitting the leaf spring 54 to act in the manner and for the purpose previously referred to. In another position of the lever 36 (Fig. 2), a recessed face 56 thereof engages a fixed pin 57 on the face 28 of the block 10. Formed on the right side of the lever 36 (Fig. 2) and, as shown on an enlarged scale in Figs. 6 and 7, are two edge or cam faces 60 and 61 which, when the lever is rocked counter-clockwise from the position shown in Fig. 1 to a position where its recessed face 56 is brought into contact with the fixed pin 57, successively engage the terminal end 25 of the coil 24 lying on the faces 27 and 28 and bend the terminal end to the position shown in Fig. 7 about the bending edge 26 of the movable member 15. Fig. 6 shows the position of the lever 36 just before the cam face 60 thereon engages the terminal end 25 and before the recessed face 56 contacts the fixed pin 57. In this position of the lever 36 (Fig. 7), the terminal end 25 is partially bent and a continued urging of the lever counter-clockwise against the fixed pin 57 causes the lever to fulcrum about the latter pin and thus move with the bearing block 34, to which it is pivoted by the pin 35, to the right (Fig. 2) to the position shown.

This last described movement of the lever 36 bends the terminal end 25 further about the bending edge 26 to the dotted outline position of the terminal end shown in Fig. 7, or in full lines in Fig. 2, the terminal end being carried forward by the advancing cam face 61, which is moving substantially parallel to the terminal end is pressed against the inclined face 19 of the movable member 15, which is held stationary at this time by the cooperating cam faces 47 and 48 on the member 15 and the plunger 43. A clearance notch is formed in the lever 36 at the lower end of the cam face 61, which provides a face 62, which clears the end convolution of the coil 24 from which the terminal end extends and lies in the plane of the lower edge of the bending edge 26, thus effecting a sharp bending of the terminal end 25. The purpose of bending the terminal end 25 to the particular angle shown relative to the longitudinal axis of the coil 24 is to over-bend it so that, upon removing the coil from the apparatus, the bent terminal end will spring back and take a set position in line with the longitudinal axis of the coil and in the plane of its outer periphery, as shown in Fig. 5.

In describing the use of the apparatus above described, it will be assumed, referring to Fig. 2, that the lever 36 is in an intermediate position between the fixed pin 57 and the plunger 43 and, further, that the coil 24 with the formed terminal end 25 has been removed from the apparatus. To mount a coil 24 in position on the arbor 22 and clamp the inner end convolutions thereof to the arbor in the manner previously referred to, the operator, with one hand, rocks the lever 36 clockwise about its pivot 35 to engage the roller

55 thereon with the plunger 43 and depresses it, whereupon the plunger cam face 48 is retracted from the cam face 47 on the movable member 15 and the spring 54 then acts to retract slightly the member away from the arbor 22 until it engages the stop pin 53. The operator then, with the other hand, inserts a coil 24 on the arbor 22 and seats its inner end against the seat 23 of the movable member 15 and, with the terminal end 24 thereof to be formed, abutting the faces 27 and 28 of the stationary member 14 and supporting block 10, as shown in Figs. 1, 6 and 8. Thereafter, the lever 36 is rocked counter-clockwise about its pivot 35 (Fig. 1), thus permitting the spring 49 of the plunger 43 to normally act to move the plunger upwardly (Fig. 2) and thereby through the cooperating cam faces 48 and 47 on the plunger and movable member 15, respectively, causing the latter member to advance and clamp the coil convolutions in the manner previously described to the arbor 22.

In this counter-clockwise rotation of the lever 36, the cam faces 60 and 61 successively engage the terminal end 25 and bend it to the position shown in Fig. 7 about the bending edge 26 of the member 15. Thereafter, in a continued counter-clockwise movement of the lever 36, it engages the pin 57, thereby causing the lever to fulcrum about the pin and, in the manner previously described, causing the terminal end 25 to be bent sharply about the bending edge 26 to the position shown in Fig. 2. To remove the coil 24 from the apparatus, the lever 36 is rocked clockwise (Fig. 2) to depress the plunger 43 and, in the manner described hereinbefore, the coil is unclamped from the arbor 22 and another coil clamped thereto.

What is claimed is:

1. An article bending apparatus comprising means for supporting a portion of an article to be bent, a bending member engageable with a free portion of the article to be bent, a pivotal and slidable support for said member effective to guide its movement during the initial bending, and means for bodily moving said pivotal and slidable support and member along a rectilinear path to cause said member to complete the final bending action.

2. An article bending apparatus comprising means for supporting a portion of an article to be bent, a bending member engageable with a free portion of the article to be bent, a pivotal and slidable support for said member, yieldable means for retaining said slidable support in one position during the initial bending, and an abutment in the path of said member for causing said slidable support to move to a second position, said member pivoting about said abutment during said latter movement of said support to impart the final bend to said free article portion.

3. An article bending apparatus comprising means for supporting a portion of an article to be bent, a bending member engageable with a free portion of the article to be bent, a support having a face for positioning the free portion of the article to be bent and upon which said portion rests in the path of said member which rides on said face, a pivotal and slidable support for said member effective to guide its movement during the initial bending, and means for bodily moving said pivotal and slidable support and member along a rectilinear path to cause said member to complete the final bending motion.

4. An article bending apparatus comprising means for supporting a portion of an article to be bent, a bending member engageable with a

free portion of the article to be bent, a support having a face for positioning the free portion of the article to be bent and upon which said portion rests in the path of said member which rides on said face, means about which the free portion of the article is bent, a pivotal and slidable support for said member effective to guide its movement during the initial bending, and means for moving said pivotal and slidable support and member along a rectilinear path perpendicular to its pivotal axis to cause said member to effect the final bending action.

5. An apparatus for bending an uncoiled end of a coil comprising clamping means for clamping a coil adjacent the end to be bent, a bending member, a pivotal and slidable support for said member, an operating lever, means responsive to the initial movement of said lever to actuate said clamping means, the further movement of said lever causing said bending member to move in an arcuate path to partially bend said end, and means in the path of said member for causing said slidable support to move said member to further bend said end.

6. An apparatus for bending an uncoiled end of a coil comprising clamping means for clamping a coil adjacent the end to be bent, a bending member, an operating lever, means responsive to the initial movement of said lever to actuate said clamping means, the further movement of said lever causing said bending member to move in an arcuate path to bend said end, and means effective during the final movement of said lever to change to path of movement of said bending member to impart the final bend to said end.

7. An article bending apparatus comprising cooperating members for holding an article to be bent, means normally acting upon one of said members to cause an article to be held by said member, means operatively connected to said one member effective when said first means is inactive thereon to cause a release of the article by said members, means about which the article is bent, and a lever engageable during movement thereof in one direction with said first means to render it inactive and in a movement in an opposite direction, causing it to act normally, said lever having a portion engageable with the article during said latter movement for bending it about said bending means.

8. An article bending apparatus comprising cooperating stationary and movable members for holding an article to be bent, means for normally urging said movable member in one direction to cause an article to be held by said members, means for urging said member in an opposite direction when said first means is inactive thereon to cause a release of the article by said members, a bending edge on said movable member, and a lever engageable during movement thereof in one direction with said first means to render it inactive and in a movement in an opposite direction, causing it to act normally, said lever having a cam face engageable with the article during said latter movement for bending it about said bending edge.

9. An apparatus for bending tangent ends of coils comprising cooperating stationary and movable members for holding a coil, means for normally urging said movable member in one direction, means for urging said member in an opposite direction when said first means is rendered inactive, said movable member having an arcuate face for clamping coil convolutions to said stationary member, means about which the tangent

end of the coil is bent, and a lever operatively associated with said movable member during a movement thereof in one direction to retract said first means to cause said movable member to be retracted from said stationary member by said second means and in a movement in an opposite direction, causing it to act normally, said lever having a portion engageable with the tangent end of the coil during said latter movement for bending it about said bending means.
